E. S. CALENO,
EXPLOSIVE ENGINE ATTACHMENT FOR BICYCLES,
APPLICATION FILED JUNE 17, 1919.

1,317,154.

Patented Sept. 30, 1919.

UNITED STATES PATENT OFFICE.

ERNEST S. CALENO, OF MONTGOMERY COUNTY, NEAR DAYTON, OHIO.

EXPLOSIVE-ENGINE ATTACHMENT FOR BICYCLES.

1,317,154.

Specification of Letters Patent. Patented Sept. 30, 1919.

Application filed June 17, 1919. Serial No. 304,951.

To all whom it may concern:

Be it known that I, ERNEST S. CALENO, a subject of the King of England, residing in the county of Montgomery, near the city 5 of Dayton, State of Ohio, have invented certain new and useful Improvements in Explosive-Engine Attachments for Bicycles, of which the following is a specification.

The principal object of my invention is 10 to provide for a bicycle, an explosive-motor attachment that is cheaply, efficiently and lightly constructed, and one which may be conveniently and compactly carried on the rear portion of the machine. The device 15 is self-contained, and its weight is materially less than that of many other types of motors employed for the purpose of propelling a bicycle.

Other important and incidental objects 20 will be brought out in the following specification, and particularly set forth in the subjoined claims.

One form of embodiment of my invention 25 is illustrated in the accompanying drawings, of which Figure 1 is a side elevational view, partly in section, of my improved explosive-engine attachment on the rear portion of a bicycle. And Fig. 2 is a top plan view of the same, with the gasolene 30 tank and luggage carrier removed.

Throughout the specification and drawings, similar reference characters denote corresponding parts.

Referring to the accompanying drawings, 35 the numeral 1 designates the rear wheel of a bicycle, and 2 the inclined bracing stay of the rear portion of the frame 3 that supports the seat 4. The numeral 5 designates a vertical support for a horizontal member 40 6 that is commonly used on bicycles to receive a luggage carrier. At its front end the horizontal member 6 is suitably secured to the stay 2.

Bolted to the horizontal member 6, preferably near its middle portion, is the foot portion 7 of a flange 8 on a horizontally disposed cylinder casting 9. To the latter is secured a similar horizontally-disposed cylinder casting 10 having a flange 11 that 50 is bolted to the flange 8, and a foot portion 12 that is bolted to the horizontal support 6.

Each horizontal cylinder casting terminates at one end in a semi-circular portion. These semi-circular portions, when bolted 55 together as shown in the drawings, form a housing for the web portions of a crank

shaft 13. Horizontally movable in the bore of each casting is a piston 14 to which is pivotally secured a connecting rod 15 that is in turn connected to the crank shaft 13. 60 Inserted in the head of each cylinder casting is a spark plug 16 connected by a wire 17 to a magneto 18 preferably carried on the left side of the motor. (See Fig. 2). The motor, as illustrated, is of the two-cycle 65 type, the explosive mixture being drawn into each cylinder through an inlet port 19 and exhausted through a port 20.

The flanges 8 and 11 terminate at their 70 top portions in right-angled extensions 21 whose upper surfaces are flush with each other to form a support for a horizontal fuel tank 22, the latter being firmly bolted to said extensions and adapted to support a luggage rack 23. The fuel tank 22 is 75 preferably elongated in shape, not only to support the luggage rack, but to coöperate with the cylinder sections in making a balanced and compact driving unit for the bicycle.

When the casting sections 9 and 10 are 80 bolted together as shown and described, and the fuel tank 22 bolted to the extensions 21, there is provided a compact and unitary driving structure for the bicycle, 85 whose rear wheel 1 is driven as follows. Fast on the outer end of the crank shaft 13, on the right side of the machine, is a driving pulley 23^a. Around the latter passes a cable 24 which in turn passes 90 around a large pulley 25 secured to the spokes 26 of the rear wheel 1, by which it is driven from the motor unit just described.

It will thus be seen that I have provided 95 a prime mover for a bicycle, that comprises few parts which may be conveniently and compactly assembled. Each cylinder and its flange portions are cast in one piece, and bolted against each other to provide a compact and balanced engine that supports above it, in small space, the fuel tank therefor. The entire structure is carried by the horizontal support 6 above the rear wheel of the bicycle. My invention reduces 100 the weight of the motor construction to the minimum without sacrificing efficiency, and decreases its cost materially.

Having described my invention, I claim:

1. In a device of the type described, the 110 combination with a bicycle, of a horizontal supporting-member secured to said bicycle above its rear wheel, a horizontally-disposed

sectional motor for operating said bicycle, a central flange on said motor extending downwardly below it and upwardly above it, said flange at its lower end secured to 5 said horizontal support, and a horizontal fuel tank mounted on the upwardly projecting portion of said flange.

2. In a device of the type described, the 10 combination with a bicycle, of a horizontal supporting-member secured to said bicycle above its rear wheel, a pair of oppositely disposed cylinder castings, each of which terminates at its inner end in an upwardly and downwardly extending flange, means for 15 securing said flanges together, right-angled foot portions on the lower ends of said flanges, secured to said horizontal supporting-member, and a horizontal fuel tank supported by the top portions of said flanges.

- 20 3. In a device of the type described, the

Copies of this patent may be obtained for five cents each, by addressing the "Commissioner of Patents, Washington, D. C."

combination with a bicycle, of a horizontal supporting-member secured to said bicycle above its rear wheel, two similar horizontally-disposed cylinder castings, a vertical flange on the inner end of each casting, 25 means for securing said flanges together to maintain said cylinder castings in horizontal alinement, a horizontal flat extension on the upper and lower end of each flange, the lower horizontal extensions being in alinement 30 for securement to said horizontal supporting member, and a horizontal fuel tank secured to the upper horizontal extensions of said flanges.

In witness whereof I have hereunto set 35 my hand this 16th day of June, 1919.

ERNEST S. CALENO.

Witness:

HOWARD S. SMITH.
